UNITED STATES PATENT OFFICE.

WILLIAM F. KELLY, OF GREENWOOD, MISSISSIPPI.

PNEUMATIC JACK.

Application filed July 5, 1921. Serial No. 482,442.

To all whom it may concern:

Be it known that I, WILLIAM F. KELLY, a citizen of the United States, and a resident of Greenwood, in the county of Leflore and State of Mississippi, have invented certain new and useful Improvements in Pneumatic Jacks, of which the following is a specification.

This invention is an improvement in jacks, 10 and more particularly relates to an improvement in pneumatic telescoping jacks.

One of the principal objects of the invention is to provide an improved jack having telescoping sections which may be extended 15 under the action of compressed air, to exert a lifting force for various purposes, such for instance, as lifting the axles of automobiles, etc.

Another object is to provide a construction 20 whereby the air may quickly and readily be dispelled from the jack to allow the collapse of the latter into normally inoperative position.

Still another object is to provide an improved automatically operating means for holding the head of the jack in raised position underneath the load and against collapsing movement so long as the load is supported, this means operating automatically 30 to allow a lowering movement of the head when the load is relieved.

A further object is to provide an improved jack of the class described which will be relatively simple, durable and efficient in 35 operation, and inexpensive to manufacture and maintain.

With these and other objects in view which will become apparent as the description proceeds, the invention resides in the 40 construction, combination and arrangement of parts hereinafter more fully described and claimed and illustrated in the accompanying drawings in which like characters of reference indicate like parts throughout 45 the several figures, and in which:

Figure 1 represents a vertical sectional view taken through a jack constructed according to my invention.

Figures 2, 3, and 4 represent sectional 50 views taken through the valve for controlling the admission of air to and its exhaust from the jack, showing the latter in various positions.

Figure 5 represents a sectional view of 55 the automatic valve showing the same in its initial or lowered position,

Figure 6 represents a similar view showing the valve in raised position,

Figure 7 represents a horizontal sectional view taken through the jack on a plane indicated by the line 7—7 of Figure 1, the view being partially shown in elevation,

Figures 8, 9, and 10 represent fragmentary elevational views of the rack member and the controlling means for the latter, 65 showing the controlling means in various positions.

In carrying out my invention, I provide an outer cylinder 5, closed at its lower end as at 6 and provided at its upper end with a threaded closure 7 having a downwardly extending annular guide flange 8 through which the inner cylinder 9 slidably extends.

At its lower end the inner cylinder is threaded into a piston 10 provided with a spaced washer 11 secured to the piston by means of screws or other suitable means 12, holding a leather cup washer 11' therebetween. The washer snugly fits the interior of the cylinder 5, and provides for effecting 70 an air-tight joint between the piston 10 and the cylinder 5.

The inner cylinder 9 is closed at its upper end at 13, and is provided with a partition 14 spaced from its upper closed end and extending axially into this cylinder 9 through registering openings in the closure 13 and partition 14 is a rack 15 having a piston 16 at its lower end provided with a spaced washer 17 holding a cup washer 17' therebetween, which snugly engages the inner wall of the cylinder 9 and provides an air-tight connection between the piston and the cylinder walls. The upper end of the rack 15 carries a detachable head 18 suitably formed, and adapted to be raised into engagement with the work when the jack is placed in 85 operation.

It may here be noted that in the operation of the jack, the rack 15 is raised with respect to the inner cylinder 9, within which, when the jack is in inoperative position, the rack is contained, and after the rack has been moved upwardly to the limit of its movement, the inner cylinder 9 moves upwardly with respect to the outer cylinder 5. Bleed holes 19 in the closure 7 of the outer cylinder allow of atmospheric pressure to be maintained at all times and above the piston 10, and the openings in the closure 13 and partition 14 of the inner cylinder allow of atmospheric pressure being con- 90 95 100 105 110

stantly maintained above the rack piston 16.

An inclined tube 20 arranged at one side of the cylinder 5 and braced thereto as at 21, serves the purpose of providing a handle 5 for the jack, and simultaneously acting as a casing for a flexible tube 22 which at its outer end is provided with a check valve indicated at 23, and a cut off valve 24, and which at its inner end extends into the 10 lower portion of the outer cylinder 5 and communicates at the point 25 with the interior of a valve cup 26 which is secured to the bottom 6 of the cylinder 5. Air from an air pump may be forced through the tubing 15 22 to the valve cup, the check valve 23 which is constructed similar to the ordinary tire valve, allowing movement of the air from the pump into the tube, and of course preventing the air from rushing back from 20 the tube of the pump.

The cut off valve 24, which is a three-way valve, is, when the air is to be introduced in the cylinder, moved to the position indicated in Figure 4, in which it will be noted that 25 a short passage from the valve 23 to the tube exists. When air is to be exhausted from the jack in order to allow the latter to collapse, the valve 24 will be moved from the position indicated in Figure 3 to that 30 indicated in Figure 2, in which it will be seen that a passage will thus be provided from the tube 22 to an exhaust port 27. The position of the valve shown in Figure 3, is that taken when the jack has been raised 35 to the desired height, and it is desired to cut off quickly the flow of air from the pump to the jack. In this instance, the air will have a free passage from the check valve 23 to the exhaust port 27, which will 40 not reach the tube 22. Thus the height to which the jack may be raised can be quickly controlled.

The automatic valve for controlling the flow of air to the inner and outer cylinders, 45 includes a cylinder 28 extending through the washer 11 to the piston 10, and threaded into said piston, said cylinder having a reduced upper extension 29 provided with a port 30 communicating through a passage 31 formed 50 in the central thickened portion 32 of the piston, with the interior of the inner cylinder 9 below the rack piston 16.

The lower portion of the tube 28 of the valve, is tapered as at 33 to snugly fit, when 55 the jack is in collapsed position into the valve cup 26, which is tapered to snugly receive the lower end 33 of the valve. A washer 34 seated in the base of the cup 26 around the opening 25 through which 60 the air enters the cup, snugly receives the lower ends of the tapered portion 33 of the valve and forms a snug joint therewith.

Slidably arranged in the tube or cylinder 28 of the valve, is a piston 35 having a de- 65 pending annular skirt 36; the piston thus

being in the shape of an inverted cup. This piston when in lowered position, closes the ports 37 cut in the lower portion 33 of the valve cylinder, and through which, when the piston is raised, air may enter the outer 70 cylinder beneath the cylinder piston 10. Bleed holes 38 provided in the piston, prevent compression or suction occurring above the piston in the space 39 defined by the valve cylinder. 75

A tube 40 is fixed to the valve piston 35, and slidably extends into the reduced extension of tube 29 of the valve cylinder, such tube 40 being open at its upper end and receiving a spring 41 which at its lower end, 80 rests against the piston 35 and at its upper end rests against the upper closed end 42 of the extension 29. The spring 41 normally tends to maintain the piston 35 of the valve in lowered position, that is, in the 85 position indicated in Figure 5.

A port 43 provided centrally of the piston 35, communicates with the tube 40, and hence establishes communication from the air inlet port 25 upwardly through the piston 35, tube 40, reduced extension 29, port 30, channel 31, to the interior of the cylinder 9. 90

It will be noted at this point that the area of the valve piston 35, exposed to in-coming 95 air is much greater than the surface exposed to the pressure which may be built up in the cylinder 9, this fact being apparent when it is noted that the area of the upper surface exposed to the pressure from the cylinder 9 100 is equal to the interior diameter of the piston tube 40, while the area of the piston exposed to the in-coming air is equal to the interior diameter of the skirt 36 of the piston. 105

The operation of the valve may be described as follows: Assuming that the rack is collapsed within the cylinder 9 and the cylinder 9 in turn collapsed within the cylinder 5, the automatic valve will be seated within the cup 26 and the parts will be in 110 position indicated in Figure 5. Air now admitted from the tube 22 through the inlet port 25 will pass up through the port 43 of the piston 35, through the tube 40, port 30, and thence to the cylinder 9 below the rack 115 piston 16. As the pressure is built up within the cylinder, the rack piston will be raised, thus extending the rack, and consequently moving the head 18 of the jack upwardly toward the work. So far, only enough air 120 pressure has been built up in the cylinder 9 to overcome weight of the rack. As soon as the head of the rack engages the work, or as soon as the piston 16 engages the partition 14 in limiting the outward movement 125 of the rack, the pressure built up in the cylinder 9 will increase. As the air is continued to be pumped, pressure on the outside or lower surface of the piston 35, will 130 gradually overcome the pressure within the

cylinder 9 and will also overcome the additional pressure of the spring 41, thus raising the piston 35 and shifting the tube 40 upwardly to cut off the port 30, and raising the skirts of the valve 35 in order to uncover the ports 37. This upward movement of the piston will occur at a point after the pressure within the cylinder 9 and the inflowing air current is equalized or counterbalanced, such movement occurring when additional pressure sufficient to overcome tension of the spring 41 is applied to the underface of the valve.

The valve having now moved from the position shown in Figure 5 to that shown in Figure 6 and the ports 37 having been uncovered, the air will now enter the outer cylinder through the ports 37 below the piston 10, and as the air is continued to be forced into the outer cylinder, this piston carrying with it the valve, will rise off of the seat 26 and will move bodily upward until the incoming current of air has been cut off.

As the piston 10 moves upwardly, the inner cylinder 9 which is fixed to the piston will be shifted outwardly, and of course will carry with it the rack 15, together with the head 18, thus raising the latter into engagement with the work and lifting the work the desired amount, or until the air controlling valve 24 in the flexible tube 22 has been moved into the cut-off position indicated in Figure 3.

When the jack is to be put away, the cut off valve 24 will be shifted into the position indicated in Figure 2, and the action of gravity causes the exhaust of air from the outer cylinder 5 below the piston 10, out from the pipe 22 to the atmosphere, thus allowing the piston 10 to move downwardly, and subsequently to exhaust the air from below the piston, which exhaust will relieve the pressure below the valve piston 35.

The spring 41 will move the valve 35 down, thus opening the port 30 and allowing the exhaust of air from the cylinder 9, thus allowing the rack to be moved by gravity down into the cylinder. As the piston 10 moves down in the normal position, the valve will again be seated in the cup 26, so that air exhausting from the cylinder 9 will pass out through the tube 22 to the atmosphere, and will be prevented from finding access to the space in the outer cylinder below the piston 10.

It will thus be seen that by attaching a pump to the pipe 22, and turning the stop-cock 24 to an operative position, allowing the air to flow into the jack, will cause the extension of the jack into position to engage and lift the work, and that when it is desired to disengage the jack, all that it is necessary to do is to turn the stop-cock to the position for opening the port 27, the gravity acting upon the parts of the jack

will cause the expulsion of the air. The action of the piston will automatically allow the admission of air to the inner and outer cylinders in turn, and will likewise automatically allow the exhaust of the air from the outer and inner cylinders in proper order.

Arranged at the upper portion of the inner cylinder 9 is the mechanism for automatically controlling the rack 15. It includes a dog 44 pivotally mounted on pin 45 arranged above the partition 14. Fixed to the dog and movable therewith is an arm 46 extending alongside the rack 15. This arm has an offset outer end 47 which rests upon the upper ends of a spring 48 arranged in a socket 49 supported on one wall of the cylinder 9 above the partition 14. The spring tends to hold the arm 46 in raised position, and consequently hold the dog out of engagement with the teeth of the rack, as shown in Figure 8.

Mounted on a pin or other suitable support 50 carried on the wall of the cylinder, is a bell crank lever 51, one arm of which is connected by a spring 52 with the nose of the dog 44, the other arm of the lever being adapted to cooperate with a lug 53 carried by the arm 46, in actuating the lever 51 in a manner to be hereinafter more fully set out.

The action of the dog and associated parts is as follows: When the rack is housed in collapsed position within the cylinder 9, the lug 54 carried by the head of the rack, engages the arm of the lever 51 to which the spring is connected, and moves this arm about the pivot 50 until the spring is passed just below the pivot point 50, when it will be stopped by engagement with the lug 53 of the arm 46. The position of the parts as thus described, is shown in Figure 9, and it will be noted that the spring 52 will in this position bring the nose of the dog just inside the edges of the teeth in such position that when the rack is moved upwardly, the nose of the dog will ride over the outer tips of the teeth of the rack. The arm 46 of the dog now holds the spring 48 slightly compressed.

As the rack moves upwardly when air is admitted into the jack, the nose of the dog rides over the teeth of the rack until the head 18 of the jack engages and receives the full weight of the load. When this happens the rack will tend to shift downwardly. This will cause the dog 44 to be moved into full engagement with the teeth of the rack, due to the fact that the upper face of the nose of the dog is cam-shaped as at 55, and this movement of the dog into full engagement with the teeth will shift the arm 46 down, thus compressing the spring 48, and also engaging the lug 53 against the free arm of the lever 51 and shifting this le-

ver back upon its pivot 50 until the spring 52 is moved upwardly beyond the pivotal point. The parts in this position are shown in Figure 10. Now it will be seen that when the load is removed from the head of the jack as the jack is collapsed, the spring 48 in expanding will throw the arm 46 upwardly, thus fully disengaging the dog 44 from the teeth of the rack.

10 The rack can now move downwardly under the action of gravity, unhampered by any engagement with the dog. As it moves downwardly and settles into nested position, the lug 54 will again engage the upper arm of the bell crank lever, thus shifting it into the position indicated in Figure 9, and again drawing the dog into such position that the tips of the teeth of the rack will be engaged by the nose of the dog.

15 It will thus be seen that the action of the dog in supporting the rack when the latter is under load, and in releasing the rack so as to be nested, is entirely automatic.

20 Although I have described the preferred embodiment of my invention, I may desire to make such changes in the construction, combination and arrangement of parts thereof as do not depart from the spirit of the invention or the scope of the appended 30 claims.

I claim:

1. A jack including an outer cylinder, an inner cylinder mounted in the outer cylinder and having a piston and engaging the 35 said outer cylinder, a rack arranged slidably in the inner cylinder and having a piston engaging the inner cylinder, means for admitting air to the outer cylinder, below the piston carried by the inner cylinder, and valve means for directing the air first 40 into the inner cylinder for raising the rack, and then into the outer cylinder for raising the inner cylinder, said valve operating when the outer cylinder is opened to the atmosphere to allow exhaust of the air first 45 from the outer cylinder and then from the inner cylinder, substantially as described.

2. A pneumatic jack including an outer cylinder, a cylinder piston arranged therein, an inner cylinder connected to the cylinder piston for movement therewith, and capable of longitudinal movement relatively to the outer cylinder, a piston slidable 55 in the inner cylinder and having means for engaging the work, means for permitting a pressure fluid to the outer cylinder below the cylinder piston, said means being operable for opening the outer cylinder to the atmosphere at will, and a valve arranged 60 in the cylinder piston and incorporating automatic operating means for admitting the pressure and fluid first to the inner cylinder and then to the outer cylinder, for expanding the jack, said valve means operating to 65 allow exhaust of the pressure fluid from the

cylinders, when the outer cylinder is opened to the atmosphere, for allowing the collapse of the jack.

3. A jack including an outer cylinder having a valve cup arranged therein, a cylinder piston slidable in the outer cylinder, an inner cylinder carried by the cylinder piston, a piston arranged within the inner cylinder and having means for engaging the work, a valve carried by the cylinder piston and including a cylinder open at its lower end and engaging in the valve cup when the jack is in collapsed position, said valve cylinder having pressure ports connecting the valve cylinder with the outer cylinder, and having a reduced tubular portion provided with a port leading to the inner cylinder, a valve piston arranged within the valve cylinder, and having an opening provided therein, said piston being provided with a sleeve 75 slidable within the reduced portion of the valve cylinder, and a spring maintaining the valve in position for closing the ports of the valve cylinder which connect with the outer cylinder and for opening the port 80 of the inner cylinder when the jack is in collapsed position, said valve having a lesser area exposed to the inner cylinder than to the cup, substantially as described.

4. A jack including an outer cylinder, 95 means for admitting a pressure fluid to the outer cylinder including a valve cup fixed with relation to the outer cylinder, a cylinder piston movable in the outer cylinder, an inner cylinder fixed to the cylinder piston, a piston arranged within the inner cylinder, and carrying means for engaging the work, and a valve carried by the cylinder piston and including means cooperating with the valve cup for preventing communicating between the cup and the outer cylinder prior to the movement of the cylinder piston to extended position, said valve including communicating ports to the outer cylinder and a communicating port to the inner cylinder, and including a spring pressed piston which closes the communicating ports to the outer cylinder and opens the communicating ports to the inner cylinder when the jack is in collapsed position, and is capable of movement to close the port of the inner cylinder and open the ports of the outer cylinder, said piston having a larger area exposed to the cup than to the inner cylinder.

5. A jack including an outer cylinder, an inner cylinder slidable with respect to the outer cylinder, a cylinder piston carried by the outer cylinder engaging the inner cylinder, a piston arranged within the inner cylinder and having means for engaging the work, and air inlet means for admitting air to the outer cylinder and for allowing the exhaust of air therefrom at will, and a valve mechanism carried by the cylinder piston 125 130

and cooperating with the inlet means for admitting air to the inner cylinder and then to the outer cylinder in expanding the jack and for allowing the expulsion of air from the outer cylinder and then from the inner cylinder from the jack, substantially as described.

6. A pneumatic jack including an outer cylinder, an inner cylinder slideable in the outer cylinder, and having a piston engaging the outer cylinder, a member including a piston sliding within the inner cylinder, a fluid inlet and exhaust means, and a valve carried by the cylinder piston and cooperating with the fluid inlet and exhaust means for admitting fluid to the inner cylinder and then to the outer cylinder and expanding the jack, and for allowing exhaust of fluid from the outer cylinder and from the inner cylinder when the jack is in collapsed position.

7. A jack including an inner and outer cylinder with one cylinder slideable with respect to the other, a piston movable in the inner cylinder, a piston movable in the outer cylinder, the piston arranged within the inner cylinder carrying a lifting member, and a fluid inlet and exhaust means, an automatically operating valve for controlling the fluid inlet and exhaust means for admitting fluid to the inner and outer cylinders for extending the jack, and for exhausting the fluid from the outer and inner cylinders when the jack is in collapsed position, and means in the inner cylinder automatically operated for controlling the position of the jack.

8. A jack including a cylinder, a rack arranged in the cylinder, and movable into raised and lower positions relatively thereto, a dog pivoted in the cylinder and having an arm extending alongside the rack, a bell crank lever pivoted to the cylinder, a spring connecting one arm of the bell crank lever with the dog for bringing the nose of the dog into slight engagement with the teeth of the rack when the spring controlled arm of the lever is depressed, a spring supported by the cylinder normally engaging the dog arm for tending to hold the dog out of engagement with the teeth of the rack, means on the rack for engaging the spring arm of the lever for moving the dog into slight engagement with the teeth when the rack is in lowered position, said dog being movable when load is applied to the rack, by coop-

eration of the nose of the dog and the teeth of the rack into full engagement with the rack, and a lug carried by the dog arm and engageable against the free end of the bell crank lever when weight is placed upon the rack, for moving the bell crank lever into a position whereby the dog will be sprung out of engagement with the rack teeth by the spring normally in engagement with the dog arm when the rack is relieved of the load.

9. A jack including a rack movable into raised and lowered position, a pivoted dog, a bell crank lever mounted on a fixed independent pivot and having a spring connection with the dog for moving the nose of the dog into slight engagement with the teeth of the rack when the bell crank lever is depressed, means for depressing the bell crank lever when the rack is in lowered position, spring actuated means normally tending to hold the dog out of engagement with the teeth of the rack, said dog being movable by the rack teeth into full engagement with the rack teeth when the load is placed upon the rack, and means for engaging the bell crank lever and moving it into raised position, when the load is placed upon the rack, whereby when the rack is relieved of the load, the spring actuated means may operate to throw the dog out of engagement with the teeth of the rack.

10. A jack including a rack movable into raised and lowered position, means for actuating the rack, automatic means cooperating with the rack for retaining the rack in raised position against the tension of a load, said automatic means becoming active for releasing the rack and operable independently of the actuating means for said rack when said rack is relieved of said load whereby to allow movement of the rack into lowered position.

11. A jack including a rack movable into raised and lowered position, means for actuating the rack, means cooperating with the rack for sustaining the latter in raised position under the weight of a load, and means automatically operable independently of the actuating means for the rack for releasing the sustaining means to permit the rack to lower when the actuating means for the rack has been released and the rack has been relieved of the load.

WILLIAM F. KELLY.
